UNITED STATES PATENT OFFICE.

EDWARD EVERETT BRAISTED, OF DAVENPORT, IOWA.

TYING DEVICE.

No. 903,051.

Specification of Letters Patent.

Patented Nov. 3, 1908.

Application filed November 1, 1907. Serial No. 400,195.

To all whom it may concern:

Be it known that I, EDWARD EVERETT BRAISTED, a citizen of the United States, residing at Davenport, in the county of Scott and State of Iowa, have invented new and useful Improvements in Tying Devices, of which the following is a specification.

This invention relates to tying devices for envelopes, packages and the like, and has for its object to provide an extremely simple device of this character which will effectively retain the tying cord and which is so constructed as to entirely obviate the liability of defacing or injuring the bundle or package to which it is secured.

With these and other objects in view, the invention is in the novel formation of package ties hereinafter fully described and claimed.

20 In the drawing,—Figure 1 is a top plan view of my improved tying device showing the same in position upon a package. Fig. 2 is a perspective view of the device, Fig. 3 is a side elevation of the same, Fig. 4 is a 25 front elevation of the same, and Fig. 5 is a rear elevation of my improvement.

As illustrated in the drawings my improved tying device consists of a single strand of wire of any desired gage, having a 30 tying eye 1 and a straight shank 2, the eye 1 being provided with a slightly upturned portion adapted for the reception of a tape or cord. The shank 2 is provided with an upturned portion 3, adapted to provide a 35 deflector for the tape or cord, and from thence is extended at an acute angle in relation to the shank 2, to provide a member 4 which is bent upon itself as at 5 to provide a hook member 6. It will be noted, by reference to the several figures of the drawings,

that the hook 6 is positioned directly above the member 4 and that its outer edge is arranged at a slight distance above said member so that the angularly arranged hook member 6 and the member 4 present an effective wedge or bite for retaining the free end of the tying cord when it is positioned upon a bundle or package.

It will be further noted that the shank 2 and member 4 are at an acute angle in relation to each other, the object of this being to bring the tying cord or tape 7 in a nearly right angular relation to each other at their point of crossing.

From the above description it will be noted that I have provided a package tying device which is extremely simple and durable, which provides means for preventing the defacing or mutilation of the article to which it is applied, and which will securely and efficiently retain the tying tape or cord.

Having thus described the invention, what is claimed as new, is:—

A tying device provided with an eye having its rear portion bent upwardly and adapted to receive the knotted portion of a tying cord or tape, a shank connected with the eye, the shank being provided with an upturned cord or tape deflecting portion and being continued at an acute angle in relation to the shank and being bent upon itself to provide a wedge shaped hook adapted for receiving and retaining the free end of the tying tape or cord.

In testimony whereof I affix my signature in presence of two witnesses.

EDWARD EVERETT BRAISTED.
